United States Patent Office

Des. 214,548
Patented July 1, 1969

214,548

CAN OPENER

E. Burton Benjamin, Highland Park, Ill., assignor to
Dominion Electric Corporation, a corporation of
Ohio

Filed Mar. 25, 1968, Ser. No. 11,117

Term of patent 14 years

Int. Cl. D8—02

U.S. Cl. D8—36

Fig. 1

Fig. 3

Fig. 4

FIGURE 1 is a perspective view of a can opener showing my new design, with a portion of a can shown in broken lines for illustrative purposes only;

FIGURE 2 is a side view of the same, the opposite side being similar;

FIGURE 3 is a top plan view of the same; and

FIGURE 4 is a bottom view of the same.

I claim:

The ornamental design for a can opener, substantially as shown and described.
